UNITED STATES PATENT OFFICE.

JOSEPH H. TALMADGE, OF CORTLAND, NEW YORK.

TWO-WHEELED VEHICLE.

SPECIFICATION forming part of Letters Patent No. 392,237, dated November 6, 1888.

Application filed October 18, 1887. Serial No. 252,698. (No model.)

To all whom it may concern:

Be it known that I, JOSEPH H. TALMADGE, a citizen of the United States, residing at Cortland, in the county of Cortland and State of New York, have invented certain new and useful Improvements in Two-Wheeled Vehicles, of which the following is a specification, reference being had therein to the accompanying drawings.

10 This invention relates to the class of two-wheeled vehicles which are designated by the trade "road-carts;" and the invention consists in a novel construction and combination of springs, which support the body on the axle, independent of the shafts or thills, and effectually relieve the body from the rocking motion usually transmitted from the horse motion.

In the annexed drawings, Figure 1 is a side elevation of a vehicle embodying my improvements, a portion of one of the shafts being broken away to better illustrate the springs by which the body is supported. Fig. 2 is an inverted plan view of the vehicle. Fig. 3 is a 15 vertical transverse section of the springs, taken on line $\alpha\alpha$, Fig. 1; and Fig. 4 is a detached side view of one of the side springs.

Similar letters of reference indicate corresponding parts.

20 A represents the axle of the vehicle; C, the shafts or thills, which are rigidly attached to the axle in any suitable and well-known manner, and B denotes the body, which is of the style designated "phaeton-body." This body 25 is support on the axle, independent of the shafts C, by means of side springs, S S, which are either rigidly mounted or hung on the axle and extend with their ends forward and rearward from the axle. Each of said side springs 30 has its two end portions bowed downward and the intermediate portion bowed upward, or curved reverse from the end portions, as illustrated in Fig. 4 of the drawings. These springs are secured at their upward bowed portions 35 to the axle, so that the springs extend forward with a downward curvature in proximity to the axle and terminate with an upward curvature, as shown at α in Fig. 1 of the drawings. The rear portion of the side spring is main- 40 tained quite low for some distance from the axle, and is thence curved upward and forward, and each end of the spring is formed with an eye, e, for the reception of the attaching shackles or couplings. On the rear ends 45 of the said side springs is hung a cross-spring, 50

D, by means of suitable swivel-couplings, c. The body is mounted at the rear end on top of the cross-spring D, and the forward end of the body is hung on the forward ends of the side springs by means of plates b b, secured 60 to the under side of the body, and having outwardly-projecting trunnions, b' b', which extend through the eyes e e of the side springs, and are provided with shoulders abutting against the inner ends of said eyes, and nuts or other 65 suitable fastenings may be applied to the outer ends of the trunnions.

The advantage of the peculiar form of the side springs, S, consists in the drop or downward bow of the forward portion of the spring 70 in front of the axle, which form imparts to said portion of the spring a tendency to be crowded rearward when subjected to a load, and its play is endwise more than vertically, and consequently the body is greatly relieved 75 from the vertical vibrations incident to the motion of the horse. A similar effect is produced on the rear extension of the spring by the horizontal portion thereof adjacent to the 80 axle.

In order to properly graduate the side spring, S, I form the same of a continuous main leaf, l, extending from end to end thereof, a short leaf or leaves, n, under the center of the main leaf and extending part way toward the front 85 and rear ends thereof, and a short leaf, O, on top of the main leaf, extending from the center rearward, as shown in Fig. 4 of the drawings.

Having described my invention, what I claim 90 as new, and desire to secure by Letters Patent, is—

In a two-wheeled vehicle, the body supported on the axle independent of the shafts by the side springs, S, secured to the axle and deflected downward in proximity to the front of the axle, and their forward extremities curved upward and connected to the body, and the rear ends of said springs extending rearward from the axle and thence curved upward and forward, and a cross-spring connected at its ends to the rear ends of the side springs and supporting the body, substantially as described and shown.

In testimony whereof I affix my signature in 105 presence of two witnesses.

JOSEPH H. TALMADGE.
